(57) **CLAIM**

The ornamental design for wireless headset, as shown and described.

DESCRIPTION

FIG. 1 is a front view of a wireless headset.

FIG. 2 is a rear view of the wireless headset of FIG. 1.

FIG. 3 is a left side view of the wireless headset of FIG. 1.

FIG. 4 is a right side view of the wireless headset of FIG. 1.

FIG. 5 is a bottom view of the wireless headset of FIG. 1.

FIG. 6 is a top view of the wireless headset of FIG. 1.

FIG. 7 is a perspective view of the wireless headset of FIG. 1.

FIG. 8 is a front view of a wireless headset.

FIG. 9 is a rear view of the wireless headset of FIG. 8.

FIG. 10 is a left side view of the wireless headset of FIG. 8.

FIG. 11 is a right side view of the wireless headset of FIG. 8.

FIG. 12 is a bottom view of the wireless headset of FIG. 8.

FIG. 13 is a top view of the wireless headset of FIG. 8; and,

FIG. 14 is a perspective view of the wireless headset of FIG. 8.
